Nicholas Müller's Design for a Clock Front

3888

PATENTED MAR-8 1870

Peter Beckerberg
Lewis Shunkle

Nicholas Müller

Inventor

United States Patent Office.

NICHOLAS MÜLLER, OF NEW YORK, N. Y.

Design No. 3,888, dated March 8, 1870.

DESIGN FOR CLOCK-FRONT.

The Schedule referred to in these Letters Patent and making part of the same.

To all whom it may concern:

Be it known that I, NICHOLAS MÜLLER, of the city, county, and State of New York, have invented a new and ornamental Design for a Clock-Front; and I do hereby declare that the following is a full, clear, and exact description thereof, which will enable those skilled in the art to make and use the same, reference being had to the accompanying photograph forming part of this specification, in which the design is represented by a front view.

This invention relates to a design for a clock-front. For convenience in description it may be divided into two parts, *a a* the upper and *b b* the lower one.

The principal feature of the part *b b* consists in a crowned female head, *c*, situated near the bottom edge, the neck being covered by an ornamental cloth, the ends of which continue toward the sides of the bottom, which are formed by large arabesques, *e*, as shown in the photograph.

Beneath the head *c*, connecting the two side arabesques *e*, is an ornamented bar, which forms the bottom edge.

The background is embellished by ornaments in relief.

The part *a a* contains the dial-hole *d*, with arabesques on each of its sides. Above it (the dial-hole) is an ornamented arch, surmounted by a scroll, twigs of fruit, and leaves emanating from it, forming the top edge of the design, as seen in the photograph.

What I claim as new, and desire to secure by Letters Patent, is—

The design for a clock-front, as herein shown and described.

Signed by me this 13th day of January, 1870.

NICHOLAS MÜLLER.

Witnesses:

PETER AECKERSBERG,
LEWIS SKINKLE.
